CONTAINER CLOSURE MANUFACTURE

George C. Erb, Forest Hills, N. Y., assignor to
 American Can Company, New York, N. Y., a
 corporation of New Jersey

Application April 12, 1946, Serial No. 661,754

7 Claims. (Cl. 113—121)

1

This invention relates to the method of preparing metallic closures for containers and has particular reference to the manufacture of easy removable sealing caps formed with an integral concentric hollow pull ring surrounding the cap.

An object of the invention is the provision of a method of preparing metallic closures for containers holding carbonated gaseous liquids such as beer and the like, wherein a smooth hollow ring is formed integral with and surrounding a sealing cap which cap may be applied readily to hermetically seal such a filled container for preserving its contents, the cap being removable without the use of tools by merely lifting and withdrawing the ring to effect opening of the container.

Another object of the invention is the provision of a method of making metallic crown cap closures for containers wherein a central portion of a blank is formed to provide a cap or closure element and wherein an intermediate annular section is cut to provide a space and an integral connection between the closure element and an outer surrounding portion to substantially separate the central and outer surrounding portions so that the latter may be formed into a hollow pull ring for use in removing such caps from sealed containers.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a crown cap closure having an integral hollow pull ring adapted for manufacture according to the steps of the present invention;

Fig. 2 is a side elevation of the cap closure and pull ring shown in Fig. 1;

Fig. 3 is a sectional view of the closure illustrated in Figs. 1 and 2 in a sealed position on the mouth of a container;

Fig. 4 is a side elevation showing the pull ring in a raised position as an incident to removing the closure from a sealed container;

Fig. 5 is a plan view on a reduced scale of a blank disc having a drawn central portion which results from the first step of the method of making the crown cap closure;

Figs. 6, 7, 8, 9 and 10 are similar views showing further steps in the manufacture of the closure;

Figs. 11, 12, 13, 14 and 15 are sectional views of the die parts of apparatus suitable for forming

2

the cap closure in a series of steps according to the present invention, Fig. 11 showing the step of forming the drawn disc of Fig. 5 and the mechanism being shown in Figs. 12, 13, 14 and 15 producing various steps in the cap closure manufacture as respectively shown in Figs. 6 to 9, inclusive;

Fig. 16 is a cross sectional view taken along the section line 16—16 in Fig. 15; and

Fig. 17 is a sectional view of the die parts of apparatus used in the final manufacturing step which produces the finished cap of Fig. 10.

As a preferred embodiment of the invention the drawings illustrate the manufacture of an easy removable closure or crown type sealing cap A and show the several method steps constituting the present invention which are used to produce such a closure.

The closure includes a hollow pull ring B (Figs. 1 and 2) formed integral with the cap A. Such a ring preferably is connected to the cap by a curved bridge C. The cap A is shaped to provide for a gasket D which forms a sealing area between the cap A and the part of a container E adapted to receive the cap. Such a cap is crimped in place according to the well known crown sealing type of closure.

This sealing cap is preferably formed from suitable metal stock F (Fig. 11) and is first blanked out as a circular disc G (Fig. 5). In the same operation the cap disc may be drawn or cupped preparatory to providing for the reception of the gasket D. These two operations are performed in a suitable die mechanism such as is disclosed in Fig. 11. A consideration of this mechanism now will be had.

A stationary die 13 is mounted upon a die support 14 of conventional press construction. The stock F is positioned over the die 13 preparatory to the blanking and drawing operation. The die 13 is removably held in place by clamp bars 15 which are bolted to the die support by cap screws 16.

The die 13 provides the female part for the blanking operation and accordingly is formed with a substantially vertical cutting wall 17 at the center. A draw block 18 is located for slight vertical movement within the opening formed by the wall 17 of the die 13 and is supported in the usual manner upon pins connected with the standard rubber or spring cushion which provides a yielding die element. The draw block 18 is apertured to provide a clearance opening 21 and a panel center block 22 projects up through the aperture. Panel block 22 is secured to the die support 14 by screws 23.

A punch 34 constitutes the male blanking element and is disposed in axial alignment with the die mechanism, the outer diameter of the lower part of the punch cooperating with the cutting wall 17 of the die 13 to blank out the disc G when the punch parts are lowered in the blanking operation. The punch 34 is carried by a crosshead 35 and is secured to the head by cap screws 36. A knockout pad 37 has sliding movement within a central opening 38 formed in the punch 34 and is carried on the lower end of a vertically disposed knockout rod 39 which extends up through the crosshead 35.

A spring 41 surrounds the lower end of the knockout rod and is disposed within a cylindrical opening 42 which merges with the opening 38 of the punch 34. This spring at the lower end rests upon the knockout pad 37 and is confined at the upper end by a wall of the cylindrical opening.

Prior to the blanking operation, the upper face of the draw block 18 is flush with the upper surface of the die 13. This plane also includes the top of the panel center block 22. The draw block 18 is held in raised position at such a time. At the time the stock F is inserted into the die mechanism, the crosshead 35 and the parts carried thereby are in raised position. The spring 41 holds the knockout pad 37 a slight distance below the surface of the punch 34.

When the punch parts descend for this operation the knockout pad 37 first engages the stock F and clamping it against the panel block 22, holds the work in position on the die. The disc G is severed from the stock as the descending punch 34 forces down that part of the stock which is engaged between the punch and the draw block 18. At the same time the center part of the disc, which is prevented from moving down by the panel center block 22, is drawn at its surrounding edges to provide a central cup section 45 (see also Fig. 5) for the disc G.

After the disc has been cut and the center portion has been drawn, the punch is raised whereupon the blanked out disc G is lifted by the rising draw block 18 and the knockout pad 37 operates to eject the disc from the punch mechanism.

In the second operation a slit disc H is produced as shown in Fig. 6. Portions of the disc G are pierced or slit to provide this stage in the manufacture of the sealing cap A and this operation may be performed in the mechanism illustrated in Fig. 12. This mechanism comprises a stationary die 52 which is held in the usual manner on a die support 53 by clamp bars 54 secured in place by cap screws 55. The disc G is placed upon the die 52 in an inverted position, i. e., the central panel 45 extends downwardly into a recess 56 formed centrally of the die 52.

The die 52 is formed with a crescent shaped slit 57 which extends from the top of the die to the top wall of a bottom recess 58. A crescent shaped draw ring 61 extends upwardly through the opening 57 in the die 52 and is an integral part of a circular draw block 62 which is movably located within the recess 58 of the die 52. The draw block 62 is supported in the usual manner upon pins connected with the standard rubber or spring cushion which provides a yielding die element. When the work is inserted for this operation the upper face of the draw ring 61 is flush with the upper surface of the die 52.

The corresponding punch parts for the die members 52, 61 include a knockout disc 64 which is carried on the lower end of a knockout pad 65 which preferably is a part of a vertically ex-

tending knockout rod 66. The rod 66 is carried in a punch crosshead 67 which is apertured centrally to allow for a slight movement of the rod 66 during lowering of the crosshead and other punch parts carried thereby.

A piercing punch 71 of crescent shape is formed on the lower end of a punch 72 which is bolted as at 73 to the lower end of the cross-head 67. The punch 72 is centrally apertured and the knockout pad 65 is loosely contained therein. The lower surface of the knockout disc 64 is slightly below the lower surface of the punch piercing die 71. It is held in this normal position by a spring 75 which surrounds the rod 66 and is confined within a recess 76 formed in the crosshead 67. The lower end of the spring rests upon the knockout pad 65 and its upper end is confined within the upper wall of the recess 76.

When the punch mechanism is lowered to perform the piercing operation on the disc G the knockout member 64 first engages the disc and holds it on the die with its drawn center panel 45 resting within the recess 56 and thus centering the work. The piercing punch 71 cooperating with the crescent shaped slit 57 in the die 52 cuts through the disc and forces the engaged stock with the draw ring 61 which recedes as the cushion support for the draw block 62 is overcome.

The piercing operation removes and slightly lowers a crescent shaped scrap piece 77 from the disc G leaving a crescent shaped opening 78 and thus forming slit disc H of Fig. 6. Upon the return of the punch mechanism the piercing punch 71 is withdrawn from the disc H while it is held by the knockout disc 64. The scrap 77 moves back into the opening 78 of the disc and when the punch element has been fully raised the disc is released and may be removed in any suitable manner at which time the scrap can be disposed of as desired.

The next operation has to do with further drawing a portion of the slit disc H so that the central part assumes the general shape of the crown cap. This produces a cap formed disc J (Fig. 7). This stage in the operation according to the present method steps may be performed by mechanism illustrated in Fig. 13 and reference now will be had to the cap forming operation.

The cap forming mechanism of Fig. 13 comprises a central forming die 81 which is mounted upon a die support 82 and is held in stationary position by cap screws 83. A circular draw ring 84 is located above the die support 82 and surrounds the die 81. The draw ring 84 has slight vertical movement relative to the die and is supported in the usual manner upon pins connected with the standard rubber or spring cushion which provides a yielding element. A holding ring 85 surrounds the draw ring 84 and limits its vertical movement. When the slit disc H is first placed upon the die 81 preparatory to the cap forming operation, the disc is still in an inverted position, the same as in the mechanism of Fig. 12. The draw ring 84 is in a raised position, its upper surface being flush with the upper surface of the die.

The support ring 85 is bolted by cap screws 86 to the die support 82. At the top the die 81 is formed with a centrally disposed recess 87 and the drawn center 45 of the slit disc H is adapted to fit snugly within this recess. This centers the slit disc on the die preparatory to the cap forming operation. The die 81 adjacent its upper sur-

face is also formed with a conical wall 88. This constitutes the male element for the cap forming operation.

The associated punch mechanism for the die 81 comprises a punch 91 which is formed integrally with or is carried on a suitable crosshead body 92. Punch 91 is formed with a central opening 93 which has different diameters. At the bottom of the punch the opening is outlined by a surrounding conical wall 94 which is coaxial with and parallel to the conical die wall 88.

A knockout pad 95 has restricted movement in the lower end of the opening 93 of the punch 91 and the bottom part of the pad normally extends down into the space adjacent the wall 94. It is held in its normal position by a spring 96 which surrounds a knockout rod 97 located in the opening 93. The lower end of the rod is connected with and carries the knockout pad. Spring 96 rests upon the top of the knockout pad and its upper end is confined against the upper wall of the adjacent part of the recess in the punch. At the bottom the knockout pad 95 is formed with a circular projection 98 which snugly fits within the drawn center 45 of the slit disc H when the punch parts descend. This centers and properly locates the disc in the die for the cap forming operation.

When the punch mechanism is lowered upon the slit disc H the projection 98 of the knockout pad 95 first engages within the drawn center 45 of the slit disc and seats that part of the disc fully within the recess 87 of the die. About the same time the punch 91 clamps the outer part of the slit disc against the upper face of the draw ring 84.

As the punch descends further the spring 96 yields as does also the spring cushion supporting the draw ring 84 whereupon that part of the disc surrounding the center 45 and inside of the crescent slit 78 is wiped down over the die 81. In this action the conical wall 88 of the die cooperates with the conical wall 94 of the punch and draws a cap section 101 (Fig. 7) having a short skirt 102 for the adjacent area surrounding the crescent shaped slit 78. The section of the cap between the ends of the slit 78 is drawn down even farther into a longer skirt 103 to provide the bridge C for the crown cap. Fig. 13 shows the fully formed disc J as it rests within the die, this being at the time the punch mechanism is on its lowermost stroke.

When the punch 91 moves up the spring 96 still holds the knockout pad 95 against the newly formed disc J whereupon the cushion operating against the draw ring 84 lifts the ring and also the formed disc so that it is brought up above the upper surface of the die 81. At the same time the lower face of the punch 91 moves up to a position above the upper surface of the newly formed disc and these combined actions strip the disc from the die mechanism.

After the cap formed disc J is completed it is usually desirable to trim the outer edge of the disc prior to further forming operations on the cap. This insures a better formed, more uniformly dimensioned easy open crown cap closure. A trimming die of simple construction is illustrated in Fig. 14 and may be used for this purpose.

The trimming die unit comprises a die 105 which is mounted upon a die support 106 and is held in place by clamp bars 107 and cap screws 108. The die 105 is apertured and a cutting wall 111 is formed in the center and adjacent the up-

per portion of the die. The diameter of this wall is the desired diameter for the trimmed disc.

A knockout block 112 is disposed within the aperture of the die 105 and this block is supported in the usual manner upon pins connected with the standard rubber or spring cushion which provides the desired yielding die element. In the normal inoperative position of the die parts the upper surface of the draw block 112 is flush with the upper surface of the die 105.

The corresponding punch mechanism comprises a punch member 113 which may be a part of a suitable crosshead 114 disposed for vertical movement and alignment relative to the die. The punch 113 is apertured at 115 and a knockout pad 116 is located in the aperture of the punch. This knockout pad is mounted on the lower end of a knockout rod 117. Normally the knockout pad is disposed in its uppermost position within the recess 115. It is held by a spring 118 which surrounds the upper portion of the rod 117 and is located within a recess 119 formed in the upper part of the crosshead 114.

The spring 118 is seated upon the lower wall of the recess 119 and its upper end engages a collar 121 which is pinned to the upper end of the rod. Recess 115 of the punch 113 is surrounded at the bottom of the recess by a conical wall 122. This wall is of a dimension and angle to snugly fit over the section 101 of the formed cap disc J.

The cap formed disc J is placed upon the die mechanism for trimming in an upright position. It is located within a locating ring 123 which is mounted upon the die 105 and which extends partially around the die. With the disc J in place and supported both by the die 105 and the draw block 112, the punch mechanism descends. The conical wall 122 of the punch moves down around the formed skirt portions 102, 103 of the disc J and further holds the disc in position for the trimming operation. The trimming operation is performed by the punch 113 forcing the disc and the draw block 112 downwardly into the position shown in Fig. 14. This cuts through the disc and leaves a surrounding trim 125 which is held in place within the locating ring 123.

As the punch mechanism is withdrawn the newly trimmed disc (designated by the letter K) moves under action of the ascending draw block 112 until it is brought back into the plane of the trim 125. Further upward movement of the punch lifts the trimmed disc K which is frictionally held in the conical wall 122 of the punch until it is free of the die. A suitable striking force is then applied to the upper end of the knockout rod 117 this being a conventional knockout action which causes the knockout pad 116 to descend sufficiently to strip the trimmed disc from the punch mechanism. The scrap trim 125 drops away from the die in the usual manner.

The next step in the formation of the crown cap has to do with initially and partially forming the ring B which it will be recalled is an integral part of the closure, the material for the ring being the stock surrounding the slit 78. This stage in the operation is performed by a punch and die mechanism illustrated in Fig. 15 and the resulting ring formed disc, designated by the letter M, is shown in Fig. 9. During this partial forming of the ring the center cap area is not altered in any manner and the trimmed disc K which is to be formed into the ring formed disc M is placed in the die mechanism in an inverted position, that is, with the cap section 101 and skirt extensions 102, 103 at the bottom.

The punch and die mechanism of Fig. 15 comprises a stationary die 131 which is secured by a cap screw 132 to a die support 133. The die 131 is formed with a central recess 135 which is non-concentric with the axis of the die. In the central recess there is disposed a draw block 136 having a locating depression 137 formed in its upper surface.

The draw block 136 has vertical movement within the recess 135 and is supported in the usual manner upon pins connected with the standard rubber or spring cushion which provides a yielding die element. A central cap screw 138 prevents displacement of the draw block 136 while allowing for the required vertical movement, this cap screw having threaded connection in the die 131.

A draw ring 141 surrounds the die 131 and is held in position by a clamping ring 142 secured by cap screws 143 to the die support 133. Draw ring 141 has vertical movement within the clamping ring 142 and relative to the die 131. Draw ring 141 is supported in the usual manner on pins connected with the standard rubber or spring cushion which provides a second yielding die element for this die mechanism.

The normal position of the vertically movable members 136, 141 is with their upper surfaces flush with the upper surface of the die 131. The locating depression 137 formed in the draw block 136 provides a centering pocket for receiving the drawn cap section 101 of the trimmed disc K in the die thus locating the disc preparatory to the ring forming operation.

The corresponding punch mechanism includes an outer punch member 151 which is secured by cap screws 152 to a vertically movable crosshead 153. The punch member 151 is recessed as at 154 to provide for certain fixed and movable punch parts, i. e., fixed and movable relative to the punch. The inner wall of this recess is circular. A central punch member 155 constitutes one of the fixed parts and is secured by cap screws 156 (see also Fig. 16) to the punch 151. The inner member 155 has an exterior circular wall which is concentric with and is spaced inside of the inner wall of the recess 154. This exterior circular wall is interrupted on one side by a straight wall 157 for a purpose hereinafter explained.

The movable parts contained within the recess 154 include a tubular clamping ring 161 which fits within the space between the central punch member 155 and the inner wall of the recess 154. The central punch 155 is slotted along parallel lines extending across the center as at 162 and this provides clearance for a connecting bar 163 which extends across the diameter of the punch and which carries the tubular clamping member 161. By reason of this construction the tubular clamping member may be raised and lowered within the recess 154 of the die 151.

The bar 163 is carried upon the lower end of a vertically disposed rod 165 which extends up through the crosshead 153. Adjacent the bottom end the rod 165 is formed with a collar 166 which is movable within a tubular recess 167 formed in the crosshead. The normal position of the movable parts of the punch including the clamping member 161 is with the lower face of the clamping member flush with the lower face of the punch 151. This is also flush with the lower face of the relatively fixed inner punch member 155.

A spring 171 surrounds the rod 165 and is located within the recess 167 of the crosshead 153. This spring normally holds the clamping

member 161 in its normal flush position. The spring 171 rests upon the collar 166 and its upper end is confined by the upper wall of the opening 167. The inner punch member 155 is formed with a pocket 168 cut in the lower face of the punch member. This corresponds roughly with the recess 137 formed in the top of the draw block 136 of the lower die. It provides clearance for the drawn cap sections 101, 102 and 103 of the trimmed disc K.

With the trimmed disc K in inverted position and with its cap center located within the recess 137 of the draw block 136 the punch mechanism descends and the punch 151 first clamps against the outer flange of the trimmed disc and presses it against the draw ring 141. Inside of this area of the flange the clamping ring 161 engages the trimmed disc and presses it down on the forming die 131. That part of the punch member 155 which surrounds the pocket 168 engages that portion of the trimmed disc K which is inside of the central area engaged by the clamping ring and presses it against the draw block 136.

As the descending punch continues its downward movement the clamping block 161 holds the engaged disc on the stationary die 131 while the parts 151 and 155 move down. The punch 151 bends over the outer edge of the disc in an annular flange 175 (Fig. 9) which extends around the entire disc. At the same time the central punch member 155 wipes down on the inner edge adjacent the slit 178 of the disc and forms an inner circular flange 176 which extends around the disc between the ends of the bridge portion C.

The result of this dual bending on the disc edges is the formation of a U-shaped section 177 which extends around the periphery of the disc excepting the region of the bridge section C. It is this U-section 177 which provides the stock for the pull ring B, the final shaping of the ring as well as a scalloping of the skirt part 102 of the cap taking place in the next and final die operation.

Fig. 10 illustrates the results of the final cap end ring forming operation which creates the easy open closure sealing cap A of Figs. 1 and 2. It is to the die mechanism used in this operation that attention is now directed.

Fig. 17 illustrates a mechanism suitable for completing the formation of the ring and for scalloping the edge of the crown cap. Such a mechanism comprises a center die block 181 which is carried on a die support 182 being held in stationary position by a cap screw 183. A draw ring 184 surrounds the die 181 and has slight vertical movement. This draw ring is retained in position by a clamping ring 185 which is secured by cap screws 186 to the die support 182. The draw ring 184 is supported in the usual manner upon pins connected with the standard rubber or spring cushion and this provides the required yielding die element for the operation under consideration.

The die block 181 is formed with a recess 187 on its upper surface and the cap center of the ring formed disc M is adapted to fit within the recess and thereby to be definitely located when placed within the die mechanism. The ring formed disc M when so located is in an upright position, i. e., in a position reversed from that of the work in the former die mechanism of Fig. 15.

The corresponding punch mechanism comprises a punch 191 formed integrally with or carried by a vertically movable crosshead 192. The

punch 191 is recessed at 193 and the surrounding walls of this recess are shaped to snugly fit over the skirt portions 102, 103 of the ring formed disc M. A knockout pad 194 is seated within the lower end of a stepped central opening 195 formed in the punch 191 this opening being contiguous with the punch recess 193. Pad 194 is secured to the lower end of a knockout rod 196 which projects up through and extends above the crosshead 192.

A spring 197 surrounds the rod 196 and rests upon the knockout pad 194 being located within the upper stepped opening 195 of the punch 191. The upper end of the spring engages the upper end of the wall of the opening and normally holds the knockout pad 194 in a lowered position wherein its lower face is substantially flush with the lower surface of the punch 191. A projection 198 is formed on the knockout pad 194 and is adapted to seat within the drawn center 45 of the ring formed disc M seated in the die 181.

When the punch mechanism descends on the first leg of its stroke the knockout pad 194 with its projecting face 198 yieldingly clamps down on the center cap portion of the disc M as it rests upon the die 181. This holds the parts against displacement for the final forming operation.

In the lower face of the punch 191 there is a circular forming groove 201 which coaxially and partially surrounds the center area of the punch being coextensive with the partially formed U-section 177 of the disc. A similar concentric hemming groove 202 is also formed in the face of the punch 191 and this extends in the region of the disc M containing the bridge C.

After the disc M has been clamped and the punch parts further descend the top edges of the flange 175 and the flange 176 of the U-shaped ring section 177 are engaged within the forming groove 201 of the punch and are forced inwardly. At such a time the U-shaped ring part is supported upon a U-shaped seat 203 formed in the upper face of the draw ring 184.

Forcing of the flange edges inwardly results in transforming the U-shape ring 177 into a completed circular section 204 (Fig. 10) constituting the body of the pull ring B. At the same time that portion of the flange 175 which is adjacent the bridge part C is engaged within the groove 202 and is bent inwardly. The final result is the formation of a hem 205 (Fig. 10) interposed between the ends of the pull ring B.

The lower tapered wall of the recess 193 of the punch 191 is corrugated or scalloped as at 206 (Fig. 17) and the spaced tapered wall at the top of the die 181 is also scalloped as at 207. The walls 206, 207 cooperate as the skirt 102 of the disc M is clamped between the walls to transform the skirt into a scalloped edge 208 (Fig. 10).

This completes the formation of the crown cap A in the die mechanism of Fig. 17. As the punch parts return to their raised position the knockout pad 194 momentarily remains in place, as the spring 197 yields, until the punch 191 is free of the work. Both punch and knockout pad then are raised clear of the crown cap A still resting upon the die member 181. During this raising of the punch the cushioned mechanism associated with the draw ring 184 causes the latter to lift the drawn cap from the die 181 whereupon the work is discharged as desired.

It is thought that the invention and many of its attendant advantages will be understood from the foregoing description, and it will be apparent

that various changes may be made in the steps of the process described and their order of accomplishment without departing from the spirit and scope of the invention or sacrificing all of its material advantages, the process hereinbefore described being merely a preferred embodiment thereof.

I claim:

1. The method of preparing easily removable closures for containers and the like, comprising piercing a crescent shaped opening in sheet material leaving a bridge section intact between a central portion and an outer surrounding portion, forming the central portion of said material within the crescent shaped opening into a sealing cap element by drawing an edge into a depending skirt, and bending the marginal edges of the outer portion outside the said opening into a pull ring circular in cross section and integral with and surrounding said cap element for providing an integral cap removing means for the closure.

2. The method of preparing easily removable closures for containers and the like, comprising forming a countersunk panel in sheet material, piercing a crescent shaped opening in said material concentric with and outside of said countersunk panel leaving a bridge section intact between a central portion and an outer surrounding portion, forming the central portion of said material within the crescent shaped opening and encircling said countersunk panel into a sealing cap element by drawing an edge into a depending skirt, bending the marginal edges of the outer portion outside the said opening into U-shaped laterally extended walls, and pressing said walls into a pull ring integral with and surrounding said cap element for providing an integral cap removing means for the closure.

3. The method of preparing easily removable closures for containers and the like, comprising cutting a disc of sheet material, forming a countersunk panel centrally in said disc, piercing a crescent shaped opening in the disc concentric with and outside of said countersunk panel leaving a bridge section intact between a central portion and an outer surrounding portion, forming the central portion of said disc within the crescent shaped opening and encircling said countersunk panel into a sealing cap element by drawing an edge into a depending skirt, bending the marginal edges of the outer portion outside the said opening into curved U-shaped laterally extended walls, and pressing said walls into a hollow pull ring integral with and surrounding said cap element for providing an integral cap removing means for the closure.

4. The method of preparing easily removable closure for containers and the like, comprising cutting a disc of sheet material while simultaneously forming a countersunk panel centrally thereof, piercing a crescent shaped opening in the disc concentric with and outside of said countersunk panel leaving a bridge section intact between a central portion and an outer surrounding portion, forming the central portion of said disc within the crescent shaped opening and encircling said countersunk panel into a sealing cap element by drawing an edge into a depending skirt, trimming the periphery of the disc to a circular outline, bending the marginal edges of the outer portion outside the said opening into curved U-shaped laterally extended walls, and pressing said walls into a hollow pull ring circular in cross section and integral with and sur-

11

rounding said cap element for providing an integral cap removing means for the closure.

5. The method of preparing easily removable closures for containers and the like, comprising piercing a crescent shaped opening in a disc of sheet material leaving a bridge section intact of one side between a central portion and an outer surrounding portion, drawing the central portion of said disc within the crescent shaped opening into a crown seal cap having a depending wall for engagement with a container, bending the two marginal edges of the outer portion of the disc outside the said opening into laterally extended legs forming U-shaped walls between the edges of said bridge section, and pressing the edges of the legs of said walls together into a pull ring integral with and surrounding the cap for providing an opening means for the closure.

6. The method of preparing easily removable closure for containers and the like, comprising piercing a crescent shaped opening in sheet material leaving a bridge section intact between a central portion and an outer surrounding portion, forming the central portion of said material within the crescent shaped opening into a sealing cap element by drawing an edge into a short skirt merging into said bridge section, bending the marginal edges of the outer portion outside the said opening into curved U-shaped laterally extended walls, and simultaneously forming said short skirt and said bridge section of the closure element into a scalloped annulus to define a crown sealing cap while pressing said walls into a hollow pull ring integral with and surrounding the said cap for providing an integral cap removing means for the closure.

12

7. The method of preparing easily removable closures for containers and the like, comprising cutting a disc of sheet material, forming a countersunk panel centrally in said disc, piercing a crescent shaped opening in the disc concentric with and outside of said countersunk panel leaving a bridge section intact between a central portion and an outer surrounding portion, drawing said central portion outside of said countersunk panel into a sealing cap element, bending the marginal edges of said outer surrounding portion into a curved interior upstanding wall extending from one side of said bridge section to the other side and a curved exterior upstanding wall surrounding said disc, pressing said interior upstanding wall and the corresponding part of said exterior upstanding wall directly adjacent into a hollow pull ring integral with and surrounding the closure, and pressing the remaining part of said exterior upstanding wall adjacent said bridge section into a hemmed edge, the said pull ring providing a cap removing means for the closure.
